BALL GAME

Carl Max Maurer, Nurnberg, Germany, assignor to
Kartanax G.m.b.H., Nurnberg, Germany
Filed Apr. 13, 1961, Ser. No. 102,795
Claims priority, application Germany Aug. 9, 1960
7 Claims. (Cl. 273—85)

This invention relates to a game involving the movement of objects and, in particular, is directed to a miniature table soccer game. In particular, the invention is a modification of the means of mounting the player figures as disclosed in my copending application Serial No. 81,097, filed January 6, 1961, for "Ball Game," now Patent No. 3,086,778.

In my aforesaid application, each player figure has a lower flexible portion which is attached to the surface of a gameboard by means of a rubber suction cup or the like. In the improvement of this invention, the lower ball striking portion of the player figure is rigid and inflexible and is detachably mounted into any given player position on the surface of the gameboard. It has been found that a very good striking or catapulting of a ball can be obtained even though the lower portion of the player figure is not flexible as heretofore but instead is rigid.

According to this invention, a depression or cavity in the surface of the gameboard forms a hole which holds snugly a press-fitted resilient plug and the rigid base portion of the playing figure is inserted into this plug. As the plug is firmly held by the wall of the cavity, the ball striking characteristic of the lower portion of the player figure is changed as compared to the bending of the figure itself inasmuch as the distortion of the holding element produced by the moving of the player figure from the vertical now occurs within the space confined by the cavity. This enables the use of a wide variety of the flexible materials for forming the plug. For example, relatively soft and flexible rubber can be used and the size of the figure holding means reduced. This results in the savings of the cost of the material and in the manufacture of the game. Another advantage exists in this construction in that the thickness of the gameboard and playing field can be substantially lessened because the distortion and catapulting momentum is absorbed by the stiff vertical wall of the cavity. Heretofore, the lower ball striking portion of each figure had to be fastened in a special hole in the gameboard in order to avoid the cracking of the gameboard.

The resilient plug is formed as a body of rotation, but a polygonal cross-sectional shape may be used. Preferably, a conically shaped plug in the form of a frustum of a cone having an acute central angle is used with the base of the cone seated in the hole in the gameboard. By so doing, the plug is urged toward the bottom of the cavity so that it is positively held from jumping out of the cavity, especially when the player figure is vigorously bent from the vertical.

The means by which the objects of the invention are obtained are described more fully with reference to the accompanying drawings, in which:

FIGURE 1 is a cross-sectional view through the resilient plug;

2

FIGURE 2 is a cross-sectional view through a portion of the gameboard showing the plug receiving cavity therein; and

FIGURE 3 is a cross-sectional view through a gameboard showing the plug and player figure mounted in the cavity.

As shown in FIGURE 1, the resilient plug 1 is composed of soft resilient rubber and has the shape of a frustum of a cone with a beveled edge 1a between the side wall and the base of the plug. The vertical hole 2 extends from the upper surface of the plug substantially through the plug at the center thereof.

The gameboard 4 is provided with a player position hole or cavity 6 having the same diameter as the diameter of the upper surface of plug 1 and having a vertical side wall 8 and a bottom 10 joined by a beveled wall 12.

As shown in FIGURE 3, the plug 1 is inserted into the cavity 6 in a press-fit. Gameboard 4 is made of a slightly flexible material so that the wall 8 tightly grips the side 20 of plug 1 and holds the plug in the manner of a dove-tail joint. The player figure 14 has its foot portion formed as a ball striking or catapulting member 16 to which is fastened a peg 18. The player figure ball striking portion and peg are all composed of a rigid non-flexible material.

25 In operation, the peg 18 is inserted into the hole 2 of the plug 1. When the player figure 14 is bent from the vertical position, the material of plug 1 is distorted but held confined in the cavity 6. When the player figure 14 is released, it springs back to the vertical, and the plug 1 is firmly held in the cavity 6 by reason of the cone 30 shape of the plug.

Having now described the means by which the objects of the invention are obtained,

I claim:

- 35 1. In a gameboard having stationary player figures placed at predetermined positions on a play field, and each figure being movable in at least its lower portion for striking a ball, the improvement in that a cavity is sunk into the gameboard at each player position, a resilient plug tightly press-fitted into said cavity, and a rigid non-elastic connection between the player figure and said plug for permitting tilting of the player figure by distorting the material of said plug.
- 40 2. In a gameboard as in claim 1, said plug having its upper surface substantially flush with the upper edge of said cavity.
- 45 3. In a gameboard as in claim 2, said rigid non-elastic connection comprising a peg joined to the lower portion of said figure and inserted into said plug.
- 50 4. In a gameboard as in claim 3, said plug having a bore hole, said peg being removably inserted into said hole.
- 55 5. In a gameboard as in claim 4, said plug having the shape of a body of rotation.
- 60 6. In a gameboard as in claim 5, said plug comprising a frustum of a cone.
- 65 7. In a gameboard as in claim 3, said plug having a polygonal cross-section shape.
